UNITED STATES PATENT OFFICE.

WILLIAM J. KELLY, OF CLINTON, IOWA, ASSIGNOR TO FOSTER BROTHERS MANUFACTURING COMPANY, OF UTICA, NEW YORK.

CUSHION-SEAT AND MATTRESS.

1,270,840.

Specification of Letters Patent.

Patented July 2, 1918.

Application filed August 2, 1915. Serial No. 43,181.

To all whom it may concern:

Be it known that I, WILLIAM J. KELLY, a citizen of the United States, residing at Clinton, in the county of Clinton and State 5 of Iowa, have invented a new and useful Improvement in Cushion-Seats and Mattresses, of which the following is a specification.

My invention relates to cushion-seats or 10 mattresses of the type employing a group of springs inclosed in pockets of fabric or other flexible material and incased in a cover of fabric, or other suitable material.

The pockets for the springs as hitherto 15 provided, while serving to a great degree to reduce the noise in the operation of the springs when they are pressed together in compressed condition, do not wholly avoid this undesirable condition, inasmuch as no 20 provision is made for insuring the interposition of fabric between the adjacent convolutions of a spring.

My primary object is to avoid the above 25 stated objection, rendering the springs noiseless in their operation, and to accomplish this purpose by a simple and economical construction.

Referring to the accompanying drawing: 30 Figure 1 is a perspective view of a cushion-seat constructed in accordance with my invention, a portion thereof being broken away to disclose interior details; and Fig. 2, a view in sectional elevation of two of the adjacent springs of the seat.

The covering of the cushion-seat is 35 represented at 3 and may be made of any desirable material, as, for example, leather or tapestry.

The springs which are inclosed within the 40 covering 3, and form the resilient supporting medium of the seat, are represented at 4, these springs being of the coiled variety as represented, and of a form commonly employed. The springs 4 are grouped together 45 in parallel relation and in any desired arrangement to fill the covering 3, it being preferred that they may be provided in parallel rows with adjacent springs directly opposite each other, as shown, though, 50 if desired, they may be arranged in staggered relation.

According to my invention each spring 4 is confined in a pocket the walls of which

are not common to the pocket of any of the other springs. The pockets, represented at 55 5, may be formed of any suitable material which is flexible and will operate to prevent noise when the convolutions of the springs strike each other. The material which I prefer to use is cotton batting which 60 is provided in sheets, though fabric of any suitable character or other material, may be employed.

In practice I prefer to wrap each spring 4 separately in a sheet of the pocket-forming material of a size slightly wider than the length of a spring, the edges of the wound sheet overlapping each other a slight distance, and thereupon tucking the ends of the sheet into the interior of the spring, as 70 shown. Thus each spring is separately wrapped and cannot contact with adjacent springs. Furthermore, by providing the separate pockets the walls of none of which 75 are common to the pockets for other springs and are free to collapse independently of each other, each pocket, when the spring therein compresses, is free to fold inwardly to become interposed between adjacent convolutions of the inclosed spring, and thus 80 noise from this cause is prevented.

It is further preferred that the springs intermediate their ends, and preferably throughout their length, be secured to the inclosing pockets, in order that by no chance 85 will the adjacent convolutions of a spring directly engage when the spring is compressed. This may be accomplished in any suitable manner, that preferred consisting of dipping the springs, prior to the wrapping 90 thereof in the pocket-forming material, into a bath of glue of any desirable kind which will cause the pockets to become firmly attached to the springs throughout the length of the latter and furthermore 95 serve to hold the inturned ends of the pockets in position.

The springs are held in the covering 3 by any suitable means, those shown being in the form of clips 6 which engage the 100 upper and lower ends of adjacent springs and connect each spring with the adjacent springs, though the springs may be connected together at a less number of points if desired.

A cushion-seat, mattress or the like, made

in accordance with my invention, may be constructed economically and the structure is rendered noiseless in use.

What I claim as new and desire to secure by Letters Patent, is:

A pocketed-spring structure comprising a spring and a pocket-forming cover formed of a sheet of material surrounding the

spring circumferentially and glued to the outer surfaces of the convolutions of the spring.

WILLIAM J. KELLY.
